T. Reaney,

Shearing Angle Irons.

No. 90,960.

Patented Nov. 16, 1869.

T. Reaney
By his Atty
J. H. Horrison

United States Patent Office.

THOMAS REANEY, OF CHESTER, PENNSYLVANIA.

Letters Patent No. 96,960, dated November 16, 1869.

IMPROVED MACHINE FOR SHEARING ANGLE-IRON.

The Schedule referred to in these Letters Patent and making part of the same.

To all whom it may concern:

Be it known that I, THOMAS REANEY, of Chester, Delaware county, Pennsylvania, have invented an Improved Machine for Shearing Angle-Iron; and I do hereby declare the following to be a full, clear, and exact description of the same.

My invention consists of certain mechanism, fully described hereafter, whereby the angle-iron ribs of vessels can be sheared without that tedious adjustment and manipulation which was demanded in shearing the said ribs by the ordinary machinery heretofore used.

In order to enable others, familiar with machinery of this class, to make and use my invention, I will now proceed to describe its construction and operation, reference being had to the accompanying drawing, which forms a part of this specification, and in which—

Figure 1 is an exterior view of my improved machine for shearing angle-iron;

Figure 2, a plan view, partly in section, and looking in the direction of the arrow, fig. 1; and

Figure 3, a side view of part of the exterior of the machine.

Similar letters refer to similar parts throughout the several views.

On any suitable frame, A, or forming a part of the same, are guides, a, for a ram, B, to which a reciprocating motion is imparted, in the present instance, by an eccentric, b, on a shaft, D, the said eccentric being adapted to an oblong opening in the ram, so as to operate on the latter in a manner which will be readily understood without description.

The shaft D has its bearings in the frame of the machine, and may be driven by a system of gearing similar to that employed in connection with punching and shearing-machines.

At the lower end of the ram is a blade, d, having two shearing-edges, at right angles to each other; and to the frame of the machine is secured a counter-blade, E, having two shearing-edges, e e', also arranged at right angles to each other, the shearing-edges of the blade and counter-blade coinciding with each other during the movements of the ram.

In shearing off the ends of bent angle-iron bars, such as are used for the ribs of iron vessels, much

difficulty has heretofore been experienced, owing to the ram carrying the upper shearing-blade having either a vertical or horizontal movement, which rendered it necessary, in adjusting the bent ribs to the shears, in some cases to up-end, and in other cases to lower the said ribs, so that they might be in a proper position to be acted on by the blades, and this necessary adjustment demanded much exertion and tedious manipulation, as well as ready judgment, from the attendants.

The object of my invention has been to overcome these difficulties, and the object has been attained, in the manner which I will now proceed to describe.

The ram B, instead of having a vertical or horizontal movement, is arranged to reciprocate, in a plane of forty-five degrees, or thereabout, to a horizontal plane, and the shearing-edge e' of the blade E, and corresponding edge of the upper blade d, are horizontal, or nearly so. The other edges of the same blades are vertical, or nearly so.

In consequence of this arrangement, the angle-iron H, shown by red lines in fig. 1, having been so applied to the machine that one flange shall bear upon the shearing-edge e' of the blade E, while the other bears against the edge e of the same blade, can be adjusted to any point, where the shears have to take effect, without the necessity of up-ending or lowering the cumbersome rib, which has to be simply supported in a horizontal position by one or more attendants, while another effects the desired adjustment.

I claim as my invention, and desire to secure by Letters Patent—

An angle-iron shearing-machine, having a two-edged shearing-blade, arranged to reciprocate in a course, at an angle of forty-five degrees, or thereabout, to a horizontal plane, in combination with a two-edged stationary blade, when the edges of the said blades are arranged substantially as herein described.

In testimony whereof, I have signed my name to this specification, in the presence of two subscribing witnesses.

THOS. REANEY.

Witnesses:

SAMUEL ULRICH,
P. G. RAMBO.
